CLAIM

The ornamental design for a jump starter as shown and described.

DESCRIPTION

FIG. 1 is a first perspective view of a jump starter showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly-dashed broken lines in the figures illustrate portions of the jump starter that form no part of the claimed design. The dash-dot broken lines in the figures show a symbolic break in its length. The appearance of any portion of the article between the break lines forms no part of the claimed design.
